UNITED STATES PATENT OFFICE.

JOSEPH C. CONN, OF BOONTON, NEW JERSEY.

APPARATUS FOR SHARPENING CUTTING IMPLEMENTS.

Application filed August 25, 1921. Serial No. 435,369.

To all whom it may concern:

Be it known that I, JOSEPH C. CONN, a citizen of the United States, and a resident of Boonton, Morris County, State of New Jersey, have invented an Improvement in Apparatus for Sharpening Cutting Implements, of which the following is a specification.

The present invention relates to an improvement in apparatus for sharpening cutting implements. One object of the improved method is to make or renew the cutting edges of cutting implements without loss of metal and an object of the improved apparatus is to provide a device whereby the cutting edge of a cutting implement may conveniently be made or renewed by pressure and re-formation of the metal rather than by abrasion. Among the advantages flowing from the practice of my improved method or the use of my improved device is the production of a cutting edge formed by compacted metal. Where the improvements comprising my invention are applied to the renewing of cutting edges or in sharpening knives or blades dulled by use, the life of the implement is prolonged since no metal is removed from the blade and the edge will last longer because the compacting of the metal renders it more resistant to deformation and attrition in normal use. Other advantages varying in degree and character will be apparent after a full description of my invention and an explanation of its mode of application and operation.

One embodiment of my invention so far as it relates to apparatus for sharpening cutting implements is illustrated in the drawings accompanying the present application and in which,

Figure 1 is a top view;

Figure 2, a side elevation;

Figure 3, an end view; and

Figure 4, a view in section showing a blade having a portion of the metal compacted to form a cutting edge.

The novelty and utility of my improved method of sharpening cutting implements such as table knives, for example, will be readily understood from a comparison with methods in common use. Among these is the method of sharpening by abrasion in which a grindstone, a whet stone, or other equivalent implement is brought into abrading contact with the metal of the knife in such a way as to form a new edge by removing

metal from each side thereof, or in some cases from only one side. In the practice of my method, however, I remove no metal but prefer to secure an edge forming attenuation by drawing down and compacting the metal locally.

While I do not intend to prescribe any single form of apparatus to carry out this method or to limit the practice thereof to such single form, I have found that apparatus embodying the elements disclosed in the above-mentioned drawings may be effectively employed. Referring to said drawings, it will appear that sharpening apparatus embodying my invention includes co-operating metal compacting elements formed and mounted to engage a longitudinally disposed portion such as the edge of a knife to impart thereto an attenuating and compacting pressure. For example, the illustrated embodiment of my improved sharpener includes a pair of similar co-operating rolls each having a cylindrical portion 1 and a substantially frustoconical portion 2, said rolls being mounted at one end in bearings forming part of spaced roll supports 3 and 4. A flat plate or base 5 is provided with holes 6 and 7 through which suitable bolts may be passed to fasten the apparatus to a table, bench, or the like where it will be readily available for use, as in a hotel or household. One of the roll supports 3 and 4 is adjustable with respect to the other, in the present case, the support 4 being movable relatively to support 3 to permit adjustment.

In order that this may conveniently be accomplished, I have provided the support 3 with a threaded recess 8 which receives the threaded bolt 9 passing through the movable support 4. Another threaded bolt passes through the fixed support 3 and its inner end forms an adjustable stop 10. By the means just described, the rolls can be rigidly positioned with their cylindrical surfaces in rolling contact and with their opposed frustoconical surfaces forming oppositely inclined sides of a V-shaped space between them. Where the rolls are mounted as shown, with their longitudinal axes vertically disposed, the base plate will have a portion of one edge cut away to form a recess or notch 11 and the base will be secured to the table or other support in such a manner that the rolls and the roll supporting portion of the base will overhang the edge of the table, said arrangement and the notch

11 being provided for a purpose to be hereinafter mentioned.

In the operation of the illustrated embodiment of my improved apparatus an edge of the knife to be sharpened will be inserted between the portions 2 of the rolls and will be drawn forward while exerting firm downward pressure. The rolls will rotate by reason of their frictional engagement with the knife and in so doing will compact the metal adjacent to the edge while it is being drawn or attenuated by such compacting action, the operation being repeated often enough to bring about the desired forming or re-forming of the cutting edge. Obviously, it is immaterial whether the knife is moved relatively to the rolls or vice versa, nor is it essential that the operating pressure be supplied manually since it is contemplated that any suitable means for effecting rolling contact between the knife and the co-operating rollers to produce a local edge forming compacting of the metal of the knife will fall within the scope of my invention.

I conceive also that a cutting implement having a cutting edge formed in accordance with my described method or by means of my improved sharpening device, constitutes a novel and useful article of manufacture comprising, as shown in Figure 4, a blade having a cutting edge in which the metal is relatively more compacted than the remainder of the blade. It is believed to be

new to cold roll a portion of a cutting implement to provide it with a cold rolled cutting edge which possesses the advantages in use hereinabove referred to, as well as others.

What I claim is:

1. A knife sharpening device comprising a pair of freely rotatable rolls arranged in unyielding peripheral rolling contact with each other as to corresponding cylindrical portions of their peripheral surfaces and in spaced relation as to corresponding frustoconical surfaces, said rolls being journaled to rotate freely by frictional engagement with a manually reciprocated knife blade.

2. A knife sharpening device comprising cooperating knife edge compacting rolls having cylindrical surfaces in rolling contact and frustoconical surfaces in spaced relation to admit a knife blade edge between them, a supporting base for said rolls provided with a notch in advance of the space between the frustoconical surfaces of the rolls to permit normal longitudinal edge compacting movement of a knife between the rolls and a notch underlying contiguous portions of the rolls to permit free passage of the blade when deflected downwardly upon its withdrawal from engagement with the rolls.

In testimony whereof, I have signed my name to this specification this 18th day of August, 1921.

JOSEPH C. CONN.
